UNITED STATES PATENT OFFICE.

ALPHEUS W. ALTORFER, OF PEORIA, ILLINOIS.

WASHING MACHINE.

Application filed June 4, 1925. Serial No. 34,994.

This invention has reference to washing machines, and it has for its principal object to improve the dolly or agitating means, whereby to produce a more effective and improved washing action on the articles deposited in the tub or container.

The invention has for a further object to provide in a washing machine, a dolly or agitator having somewhat the contour of a saucer and occupying a space substantially equal to the cross-sectional area of the tub or container and supported to be oscillated next adjacent the bottom of the tub and provided with a perforated bottom and upstanding fins or baffles. The latter serving to keep the articles to be washed in constant agitation and the upturned peripheral portion of the dolly or agitator serving to direct the articles upwardly and inwardly as the centrifugal action of the dolly or agitator moves the same outwardly. The result is a more effective washing action and the upward movement of the articles at the peripheral portion of the dolly or agitator prevents the articles getting under the edge of the dolly or agitator and becoming damaged or torn.

That the invention may be more fully understood, reference is had to the accompanying drawings, forming a part of the present description and illustrating a preferred embodiment of the invention, in which:

Figure 1 is an elevation, in section, showing a washing machine embodying my invention, and

Figure 2 is a partial plan view of my improved dolly or agitator.

Like characters of reference denote corresponding parts throughout the figures.

The tub or container 1 is preferably cylindrical in shape, not unlike those in general use in machines of like character, except that it is made possible, with the use of a washing element, such as I show and describe, to provide a tub or container with a comparatively larger washing surface area than is ordinarily found in machines of this class. Said tub or container is supported by standards or legs 2. The bottom wall 3 of the tub or container, when using my improved dolly or agitator, may be substantially flat, as shown.

Extending upwardly through the bottom wall 3 of the tub is an operating shaft 4, and said shaft on its lower end has a gear wheel 5 engaged by a rack or segment gear 6 connected to and adapted to be oscillated back and forth by a shaft 7. Connected to said

shaft 7 is a crank 8 arranged to be operated by suitable means, not shown, from any suitable source of power. The gear wheel 5 and the rack or segment gear 6 may be encased in any suitable housing 9.

The shaft 4 extends up through and has bearing in a stem or casing 10, open at its upper end and to the upper end of said shaft 4 is connected a coupling member 11 having a depending flange 12 encircling the upper end of the stem or casing 10 and the extended axial portion of said member 11 is preferably square, as at 13, to provide a convenient mode of attaching the dolly or agitator, to be described, thereto, and to detach the same therefrom. The lower end of said stem or casing 10 passes thru the bottom wall of the tub, and any suitable means is employed to seal the connection between said stem or casing and said bottom wall to prevent leakage around said stem or casing.

The dolly or agitator is designated 14 and has, as shown, somewhat the contour of a saucer and occupies a space substantially equal to the cross-sectional area of the tub or container and is supported to be oscillated next adjacent the bottom of the tub. The base 15 of the dolly or agitator is substantially flat and is perforated as at 16 and the peripheral portion 17 of said dolly or agitator is curved upwardly and outwardly while its edge, next adjacent the side wall of the tub is provided with a bead 18. Furthermore said dolly or agitator is provided with a plurality of radially arranged upstanding fins or baffles 19, disposed in spaced relation and preferably stopping short of its peripheral portion and center thereof.

Axially disposed and upstanding from the base 15 of the dolly or agitator is a tubular sleeve-like portion 20 having a shouldered throat 21 provided with a squared opening therethrough adapted to fit over the squared extension of the coupling member 11. Such a construction provides a simple means by which the dolly or agitator may be attached to and detached from the shaft 4.

As will be seen, the height to which the shaft 4 extends up into the tub or container 1 and the position of the dolly or agitator thereon, inasmuch as the dolly is supported from the upper end of said shaft, will determine the position of the fins or baffles in the water in the tub or container and the relative positions of such fins or baffles to the normal water line in the tub; also the position of the base

of the dolly or agitator to the bottom wall of the tub. The post or stem connection formed between the shaft 4 and the dolly or agitator is such, that the upper end thereof is sufficiently far above the water, when agitated, to prevent leakage through the top of said stem.

In Figure 1 I have illustrated the normal water line and the relation of the baffles of 10 the dolly thereto and I have also shown by arrows the approximate movement of the articles in a radial direction from and toward the axis of the tub, resulting from the agitation and centrifugal action set up by reason 15 of the oscillation of the dolly and the upturned peripheral portion of said dolly.

In operation, the articles are placed in the tub on the dolly and as the latter is oscillated, the articles are constantly kept in agitation 20 through the contact of the fins or baffles, and by reason of the agitation of the water, and then through the centrifugal action set up, the articles move outwardly and upwardly and 25 then inwardly and downwardly. The upturned peripheral portion of the dolly forcing the articles upwardly and away from the side wall of the tub preventing the articles being drawn under or getting under the edge 30 of the dolly and being damaged or torn. The perforations in the bottom wall of the dolly give free circulation of the water and air

therethrough and assist in a more efficient washing action. The dolly may be removed at will for cleaning and as shown, a simple operative connection is provided between the 35 dolly and the operating shaft.

What I claim is:—

1. A dolly for a washing machine comprising a substantially flat perforate base member provided with an upwardly and outwardly flared peripheral portion, baffles extending upwardly from said base, and an upstanding axially disposed sleeve member arranged at its upper end for connection with a driving 40 part.

2. In a washing machine, in combination, a tub, a driving shaft extending through the bottom of the tub, a sleeve surrounding said shaft, a dolly loosely mounted on said shaft but positively driven, said dolly having a perforate bottom substantially parallel to the bottom of the tub and terminating in an upwardly and outwardly flared portion near the sides of the tub, and upstanding baffle 50 members on said dolly of materially less length than said dolly and spaced approximately midway between said driving shaft and the periphery of said dolly.

In witness whereof, I have hereunto affixed my hand this 2nd day of June, 1925.

ALPHEUS W. ALTORFER.
